Patented Dec. 18, 1923.

UNITED STATES PATENT OFFICE.

MENDEL P. WEINBACH, OF COLUMBIA, MISSOURI.

ELECTRIC FUSE IGNITER.

Application filed April 21, 1920. Serial No. 375,546.

To all whom it may concern:

Be it known that I, MENDEL P. WEINBACH, a citizen of the United States, residing at Columbia, in the county of Boone and State 5 of Missouri, have invented certain new and useful Improvements in Electric Fuse Igniters, of which the following is a specification.

For mining and blasting operations, time fuses are generally used. These fuses are 10 generally lighted by means of a flame, which being unconfined, frequently causes damage and is therefore dangerous and objectionable.

The present invention provides a lighter 15 which confines the ignition and enables the fuse to be positively lighted at all times and under all conditions and obviates flame.

The drawings illustrate a preferred embodiment of the invention. However, it is 20 to be understood that in adapting the same to meet different conditions, various changes in the form, proportion, and minor details of construction may be resorted to without departing from the nature of the invention as claimed hereinafter.

Referring to the drawings hereto attached:—

Fig. 1 is a sectional detail of an end portion of the igniter.

Fig. 2 is a central section of the handle portion of the igniter.

Fig. 3 is a sectional view of the end portion of the igniter with the grip means omitted showing the parts on a large scale.

Fig. 4 is a horizontal section of the line 4—4 of Fig. 3.

Corresponding and like parts are referred to in the following description and indicated in the several views of the drawing by like reference characters.

The igniter comprises a member 1 which is formed with a centrally disposed opening 2, which is enlarged at one end as indicated at 3. The handle or member 1 may be of 45 any form and any suitable insulating material. A socket 4 is fitted within the outer end of the enlarged portion 3 of the opening and is internally screw threaded. An insulated contact 5 is provided in the 50 bottom of the socket 4 and a wire 6 leads therefrom and passes through the opening of the handle 1. A wire 7 connects with the socket and is electrically insulated from the contact 5. A wire 8 extends through 55 the opening of the member. The wires 7 and 8 are spaced apart as indicated at 9, and

and are adapted to be electrically connected by means of a circuit closure 10, which is actuated by means of a push button 11 set in an opening formed in a side of the member 1, opposite the enlarged portion 3 of the central opening. The wires 6 and 8 connect with any source of electric supply, which may consist of a battery or other form of generator.

A plug 12 is adapted to make screw thread connection with the socket 4, and embodies a shell 13, which is screw threaded to match the screw threads of socket 4. A contact 14 is located centrally of the outer end of the plug 12 from which it is insulated as indicated at 14' and is adapted to make electrical connection with the contact 5 when the plug is screwed into the socket 4 to the limit of its movement. The shell 75 13 is adapted to make electrical connection with the socket 4. Two wires 15 and 16 have their ends connected with, respectively, the contact 14 and the shell 13, as shown most clearly in Fig. 3. These wires extend 80 along the sides of a rod 17, which may consist of any suitable insulating material. The rod 17 is connected at one end with the plug 12. An element resistance 18 connects the outer ends of the wires 15 and 16 85 and may consist of a short length of platinum wire or metal or alloy of any nature, which will become sufficiently heated on the passage of an electric current therethrough to effect the ignition of a fuse. This 90 resistance 18 may be considered as the igniter proper, since it becomes red hot on the passage of the electric current therethrough, whereby it is enabled to light the fuse or other part to be ignited. A tube 19 incloses 95 the rod 17, the wires 15 and 16 and the igniter 18, and projects a short distance beyond the igniter 18. The tube 19 is electrically insulated from the wires 15 and 16. Suitable insulating material 20 is interposed be- 100 tween the parts 17 and 19, and may consist of plaster of Paris or other binding material. The tube 19 is of such internal diameter as to readily receive the fuse 21, which may be easily slipped into the outer 105 end of the tube, when it is required to light the fuse. An element 22 is fitted upon the tube 19 exterior to the shell 13 and plug 12 and provides grip means carrying the igniter proper 18. The element 22 110 is grasped in the hand when screwing the plug 12 into the socket 4 thereby connecting

igniter 18 through member 1 to the source of electrical supply of current.

In practice the wires 6 and 8 of the igniter are connected to a battery or other source 5 of electric supply. The fuse 21 to be ignited is inserted in the outer end of the tube 19 until it comes in contact with the igniter 18 while the push button 11 is moved inward to close the circuit and the igniter 18 becoming sufficiently heated, 10 lights the fuse. It will be understood that there is no flame and that the ignition is confined, thereby obviating the dangers incident to an unconfined flame when igniting 15 fuses in mining and blasting operations.

Having fully described my invention, what I claim as new and desire to secure by Letters Patent is:—

1. A fuse igniter comprising an elongated 20 tube of the same diameter throughout its entire length for receiving the end of the fuse, and an igniter disposed within the tube for igniting the fuse when brought in contact therewith, said igniter being 25 spaced from the tube below the point of contact whereby a closed space is provided below the fuse for confining the ignition.

2. A fuse igniter, comprising an elongated tube of the same diameter throughout 30 its entire length adapted to receive the end of the fuse to be ignited, and an electric igniter disposed within the tube, for contact with the fuse, and means for insulating the igniter from the tube, said means 35 coaxing with the end of the fuse to provide a closed space for confining the ignition.

3. A fuse lighter comprising a handle member having electric conductors disposed 40 therein, one of which is provided with a gap, and with circuit closing means for bridging the gap, and a socket for a fuse adapted to be coupled to said member, and containing fuse ignition means in the

bottom thereof adapted to make electric connection with the conductors of the handle member when coupled thereto, and insulating means in said socket providing a space around the ignition means and below the fuse for confining the ignition.

4. A fuse igniter, comprising a handle 50 member, conductors disposed within the member, one of the conductors having a gap, a circuit closure for bridging the gap, a plug adapted to be coupled to the member, electric conductors supported by means of 55 the plug, and adapted to make electric connection with the conductors of the member when the plug is coupled thereto, a resistance connecting the conductors of the plug and constituting the igniter, and a protector 60 tube carried by the plug for holding the fuse, said tube being spaced from the igniter to provide a closed ignition-confining space below the tube.

5. A fuse lighter comprising a handle 65 member and a fuse member for detachable association with the handle member, electric conductors disposed in the handle member, one of which is provided with a gap, a sliding member for bridging the gap, a slide 70 carried by the outer end of the handle and having the conductors connected thereto, a plug carried by the fuse receiving member for engagement in the socket, a conductor wire in the fuse member connected with the 75 terminals of the plug, and a resistance wire disposed in the conductor wire carried by the fuse receiving member disposed adjacent to the outer end thereof.

In testimony whereof I affix my signature 80 in presence of two witnesses.

MENDEL P. WEINBACH.
